(57) **CLAIM**

The ornamental design for a combined set of fork and spoon with a knife, as shown and described.

DESCRIPTION

FIG. 1 is a perspective view of a combined set of fork and spoon with a knife showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof;

FIG. 7 is a bottom view thereof;

FIG. 8 is an exploded perspective view showing that the spoon is disassembled from the fork.

FIG. 9 is a perspective view showing that the spoon is assembled with the fork in another direction; and,

FIG. 10 is a perspective view showing a state of use thereof. The broken line portion of the figure drawings is included to show unclaimed subject matter only and forms no part of the claimed design.
